BENJAMIN DE LACY, OF BROOKLYN, NEW YORK, ASSIGNOR TO WILLIAM VOGEL & BROS. INC., OF BROOKLYN, NEW YORK, A CORPORATION OF NEW YORK

CAN-CLOSURE STRUCTURE AND PROCESS

Application filed July 23, 1927. Serial No. 207,838.

My invention relates to a new and improved closure structure for cans and similar vessels, and to methods of producing or applying such closures.

5 The structure includes a cap of pressed sheet metal of generally cupped or dished formation, having a top flange, a side wall of substantial depth, and a lower portion which is formed with curvatures or depressions, or 10 as otherwise stated, is initially formed to provide an area or amount of metal available for re-forming or bending, after the cap is positioned in an opening in the wall of a can or similar vessel, to secure the cap in position 15 and seal the opening, without cracking or rupture of the cap; such cracking or other injury being avoided by the stated initial formation or deformation of the lower portion of the cap, which provides, in effect, excess 20 metal available for bending by pressing or spinning operations to effect the connection of the cap with the can wall surrounding the orifice therein.

More particularly described with reference 25 to the present specific embodiment, which represents a preferred form of cap structure, the cap bottom is formed with an annular depression surrounding a relatively elevated flat central portion, and after the cap is inserted in the can aperture, the side wall is 30 distorted or "spun" outward to form a substantially annular horizontal bead or flange, the original annular depression providing metal available for the formation of this 35 bead or flange without excessive strain upon the metal, or possibility of cracking or rupture.

The process included in the invention consists, in one aspect, in pressing or otherwise 40 distorting the lower or inner portions of a cap embodying the features above described, to produce a horizontal or lateral flange or bead which interlocks the cap with the can wall opening, and in such operation changing 45 the original shape of the inner or bottom portion of the cap and in effect taking up excess metal originally provided therein and forming such excess metal into a locking flange or bead, with avoidance of undue strains upon 50 the metal and, therefore, without cracking or

rupture. In another aspect, the complete process includes the production of a cap in the original form above described, its insertion in the can aperture, and subsequent deformation in the manner just above stated. 55

The accompanying drawings illustrate one representative structure and also explain one representative performance of the process. After considering these examples, skilled persons will understand that many variations 60 may be made within the principles of the invention, and I contemplate the employment of any structures, and any variations in the process or method, which are within the scope 65 of the appended claim.

Fig. 1 is a vertical section (that is, a section in an axial plane) of a cap, representing one suitable form of this part of the invention structure.

Fig. 1' is a bottom plan of the same. 70

Fig. 2 shows the cap inserted in a can aperture, ready for fastening, and also sufficiently explains the fastening operation; and

Fig. 3 shows a cap fastened or locked in position and also represents the complete 75 closure structure, including a can wall with its aperture and the cap located therein to form a sealed closure.

Fig. 2 shows the upper part of a can or similar vessel, usually of sheet metal, having a 80 wall 1, which may be the top wall of the can, provided with an opening 2 for the convenient filling of the vessel, after which the opening is to be closed and sealed by a suitable cap and plug. The opening 2 may be defined by 85 a plain, thin edge of the sheet metal top 1, or otherwise the metal adjacent the opening may be pressed or spun to provide an inward extending narrow flange or shallow annular wall 3.

The cap C, Fig. 1, which forms an important part of the invention structure, is of sheet metal and is originally pressed, as shown in that figure, in generally dished or cupped form, so that it includes a side wall 4 of substantial depth, a top flange 5 projecting outward, and a lower or inner portion including formations to provide, in effect, excess metal available for the subsequent bending or spinning operations which secure the cap in posi- 100

tion. A sufficient example of such lower formations is given in Fig. 1, wherein there is formed in the cap bottom an annular depression 6 of preferably curved sectional contour, surrounding a flat central portion 7, which is substantially elevated in relation to the bottom 8 of the annular depression. There is thus provided in the cap bottom an amount of area of metal substantially in excess of that needed to merely close the cap bottom. For practical purposes all outlines of the cap are usually round as shown in the bottom plan, Fig. 1^a; thus, the side wall 4 is substantially cylindrical or else slightly conical or tapered, and the flange 5 and the various bottom formations 6 and 7 are of substantially round or annular contour, although in some cases the general form or contour of the cap might be oval or even polygonal.

20 The bottom portion 7 is usually located in a plane well below that of the top flange 5, to permit proper and convenient application of suitable bending or spinning tools to the side wall in the act of securing the cap in position.

A cap formed as above described is inserted in the opening 2 as shown in Fig. 2, with the flange 5 resting upon the outer face of the can-top-wall. The side wall 4 thereupon projects through the opening, its upper portion being in engagement with the opening-wall 3. When the side wall 4 is substantially conical or tapered a tight fit in the can wall opening may be secured; but otherwise the side wall 4 may be practically cylindrical and dimensioned to permit ready application into the can opening and in such cases slight looseness will be unobjectionable and will be taken up sufficiently in the act of securing 40 the cap.

A suitable bending or spinning tool, such as 9 or a plurality of such tools, in accordance with common practice in this art, is then applied to the side wall in a horizontal plane 45 above the cap bottom portion 7 and below the plane or zone of the can aperture wall 3, and the side wall 4 is bent or spun outward to form a substantially hollow, annular, horizontally-projecting bead or flange 10, as indicated in dotted lines in Fig. 2 and in full lines in Fig. 3, which shows the completed closure structure. In this operation the metal included in the annular depression 6 is bent, taken up, or outwardly straightened to produce the substantially flat cap bottom 11, Fig. 55 3, and concurrently the lower part of the side wall is deformed outwardly in close contact with the bottom edge of the aperture wall 3, the excess metal originally provided 60 in the cap bottom structure providing for the formation of the annular locking bead or flange 10 without any severe strain upon the metal or possibility of cracking or breaking it.

In final form the complete closure structure 65 comprises the can top wall 1 with its opening

formed as above described and the cap C, sealed therein, as above fully described.

In distinction from such old structures and methods, I provide a cap which is originally formed with excess metal available for deformation, and after the cap is positioned in the can aperture it is pressed or deformed in another manner or in a different direction, and at the same time the excess metal provided by the original formation of the cap is formed into the locking bead or flange without any excessive strain upon the metal and with avoidance of cracking or rupture. In this way I not only produce a structurally-superior closure, but provide a more rapid and economical process of production, since particular care need not be taken in the applying operation to avoid cracking or breaking the cap material.

I claim:

In a can closure structure having a hollow cylindrical sheet metal body portion for use as a sealing insert in the aperture of a wall of a can or similar vessel, an outwardly extending sealing piece for contacting flatly the 90 outerside of the wall around the aperture, and a raised circular part of considerably less diameter than the internal diameter of the body portion disposed inside the body portion, a curved portion between the raised part 95 and the body portion, said curved portion and said body portion reaching respectively below and above the plane of the circular part and together comprising material for expansion outwardly to make a sealing section adapted to lie against the innerside of the wall surrounding the aperture, said circular part and said curved portion being spun into a flat plane, whereby to secure and seal the attaching device in place while avoiding excessive strain upon the metal and consequent rupture or cracking thereof.

In testimony that I claim the foregoing as my invention, I have signed my name hereto.

BENJ. DE LACY.
